PROSPECTING FOR OIL

Edward B. Peck, Elizabeth, N. J., assignor to
 Standard Oil Development Company, a corpor-
 ation of Delaware

Application September 2, 1937, Serial No. 162,076

3 Claims. (Cl. 23—232)

The present invention resides in a method for locating sub-surface oil deposits. More particularly, it is an improvement in a known method for oil prospecting by soil gas analysis.

5 It has been ascertained that the presence of methane in soil gas is not, per se, evidence of the existence of a sub-surface oil deposit. Such deposits are indicated by the presence in soil gas of hydrocarbons higher than methane, such as ethane, propane, etc. The detection of these higher hydrocarbons in the soil gas, however, has presented a vexatious problem, since there is no chemical test which will directly distinguish ethane from methane, and the dilution of 10 these gases in the air is so extensive that isolation of the hydrocarbon constituents by liquefaction and fractionation is impossible.

The method most commonly employed for the analysis of gases for their hydrocarbon content 20 is the method known as the carbon dioxide shrinkage method. According to this method, the volume of the gas sample is first measured. It is then subjected to combustion. The amount of CO₂ produced is measured and the resulting 25 volume of gas is measured. The ratio of the volume shrinkage to the CO₂ produced is relied upon to indicate the character of the hydrocarbon in the gas. This method is not applicable to the problem of soil gas analysis, however, because the volume of gas required to produce a measurable amount of CO₂ is so great that the volume shrinkage would be within the limits of 30 experimental error.

According to the present invention, sub-surface 35 face deposits of oil are detected by collecting a sample of soil gas in the suspected area and subjecting this gas to a treatment suitable for establishing the concentration of and the average number of carbon atoms per molecule of 40 the hydrocarbons contained in the gas. More specifically, the sample of soil gas is subjected to combustion, the temperature rise due to combustion or the total heat of combustion is measured, the carbon dioxide resulting from the combustion is measured so as to establish the total 45 carbon content of the sample of gas, and this carbon content is correlated with the temperature rise or the total heat of combustion, as the case may be, to give a relation indicative 50 of the number of carbon atoms per molecule of hydrocarbon in the sample.

In carrying out the method of the present invention, the total heat of combustion of the hydrocarbons in the gas sample may be measured by any conventional micro-calorimeter.

This calorimeter may take the form of a combustion chamber in which are arranged electrical resistances, the value of which changes with change in temperature. The change in resistance is recorded on a galvanometer which 5 may be so calibrated as to directly record heat of combustion. Likewise, the measurement of the carbon dioxide in the products of combustion may be made in any known manner, such as by absorption of the carbon dioxide in soda lime or 10 by titration of a solution of caustic soda into which the combustion products are fed. In order to eliminate any calculation, it is possible to employ an amount of caustic soda just sufficient to neutralize a molecular volume of carbon 15 dioxide and to run the analysis until the caustic soda is exactly neutralized.

Inasmuch as one step of this method is an accurate measurement of the amount of carbon dioxide produced by the combustion of the hydrocarbons in the gas undergoing treatment, it is necessary that this gas be freed from any naturally occurring carbon dioxide before being burned. This is done in the conventional manner by feeding the gas through soda lime or any 20 other agent capable of removing carbon dioxide. Generally, the same agent will remove any H₂S 25 present in the gas.

Since every apparatus will have its own peculiarities with regard to the combustion rate, 30 heat loss, etc., it is desirable, in the practice of the method of the present invention, to first calibrate the apparatus. This is done by determining total heats of combustion of samples containing measured amounts of certain hydrocarbons. For example, a gas mixture containing 35 600 parts per million of methane is passed through the apparatus and its total heat of combustion measured. Next, a sample containing 300 parts of ethane per million is subjected to 40 combustion in the apparatus and its total heat of combustion measured. The same procedure is followed with a gas mixture containing 200 parts per million of propane and a gas mixture containing 150 parts per million of butane. All 45 these gas mixtures have the same carbon content. In this way, four points are obtained on a curve indicating the total heat of combustion of gases having the same carbon content and each having as its sole hydrocarbon constituent 50 a different member of the methane series.

This procedure may be repeated with gases having different carbon contents. The greater number of curves so produced the easier will be 55 the evaluation of the unknown sample. When

the unknown sample is tested, its total heat of combustion and the amount of CO_2 produced by combustion are measured. The amount of carbon dioxide formed is employed in selecting the calibration curve upon which the measured heat of combustion is to be read.

The method may be somewhat simplified by so calibrating the apparatus that only the temperature rise in the combustion chamber and 5 volume of carbon dioxide in the products of combustion need be determined. That is to say, in preparing the calibration chart, temperature rise in the combustion chamber for a given rate of flow is plotted against carbon dioxide content 10 of the combustion products. For example, 1000 cu. ft. of a gas containing a known amount of methane is passed through the apparatus at a given velocity and the content of carbon dioxide in the combustion products is measured. The 15 same procedure is followed with gases having the same carbon content present as ethane, propane and butane respectively. Temperature rise in the combustion chamber is then plotted against number of carbon atoms in the hydrocarbons in the gas to produce a curve characteristic of a gas mixture producing the particular amount of carbon dioxide. Then, in testing an 20 unknown gas, the same volume is fed through the apparatus at the same rate. Temperature rise is measured and the amount of carbon dioxide in the combustion product is determined. This amount of carbon dioxide is employed in 25 selecting the curve on which the temperature rise is read and from which the average number 30 of carbon atoms per molecule in the hydrocarbons contained in the gas is determined.

The present invention may be better understood by reference to the accompanying drawings in which Fig 1 is a front elevation, partly in 40 section, of an apparatus suitable for conducting the necessary analysis, Fig. 2 is a calibration chart showing the relation between total heat of combustion and number of carbon atoms in hydrocarbons contained in gases having the same 45 carbon content, present as hydrocarbons of the methane series, and Fig. 3 is a calibration chart showing the relation between temperature rise in the combustion chamber with gas flowing at a specified rate and number of carbon atoms in 50 the hydrocarbons contained in the gas.

Referring to Fig. 1 in detail, a sample of gas to be tested is fed into tower 1 packed with soda lime or any other reagent for the absorption of carbon dioxide. The purified gas then passes 55 through a tube 2 to combustion chamber 3. Arranged in line 2 is a pressure control device 4 which controls pressure in line 2 simply by liquid level head and a flow meter 5 of conventional design.

60 Arranged in combustion chamber 3 is an open end of the tube 6 which has its inlet near the top of chamber 3 and its outlet immersed in a solution 7 of a reagent capable of reacting with CO_2 .

65 Arranged in tube 6 is a wire 8 having a thermojunction 9 located near the top of tube 6 and another thermojunction 10 located near the bottom of tube 6. Wires A, B and C are attached to these junctions, wire B being common to both 70 junctions. These wires are connected in a circuit containing measuring instruments which may be calibrated to record temperature directly.

75 It is to be understood that the temperature measuring arrangement described above is only illustrative. Any conventional thermocouple or

pyrometer may be employed for the temperature measurement so long as one measurement is made at the top of tube 6 and another at the bottom. Of course, the instrument employed must be highly sensitive, preferably capable of recording 5 temperature changes of at least .001° C. A check may be provided on these temperature measurements by taking measurements at intermediate points.

Tube 6 is packed with pieces 11 of oxidation 10 catalyst. This catalyst may be copper oxide, a chromate, a manganite, such as manganese manganite or hopcalite, or any other of a number of known oxidation catalysts. It may be desirable to coat the wire used for temperature measurement with the oxidation catalyst. Combustion chamber 3 is surrounded by an electric furnace 12, the purpose of which is to bring the combustion chamber to a temperature necessary to initiate combustion of the hydrocarbons contained in the gas sample and to maintain a substantially uniform temperature around tube 6.

The temperature differential between the thermocouples in tube 6 gradually reach a steady state with constant flow of gas and it is this 25 final steady temperature which characterizes the measurement. It is not always possible to reach a steady state in tube 6 with a given volume of gas flowing through the apparatus, therefore through stop cock 16 the flow of gas may be directed to either absorber vessel 13 or 13' until a steady state is reached, after which the stream may be diverted through vessel 13 where the total volume of gas required to produce a definite amount of CO_2 may be measured.

The vessel 13 carrying the solution for measuring the CO_2 may be replaced by a tube packed with a solid material, such as soda lime, capable of absorbing CO_2 . When this expedient is employed, it may be advisable to interpose between 40 the combustion chamber and the CO_2 absorption tube a tube packed with a dehydrating agent such as manganese perchlorate. It is advisable to provide the exhaust tube 14, which conducts the remainder of the combustion product from 45 the system, with a water seal of conventional design or any other device for preventing the leakage of atmospheric gases into the apparatus from that end.

In Fig. 2 is shown a series of curves obtained 50 by plotting total heat of combustion per unit volume of gas against the number of carbon atoms in the hydrocarbons in the gas. Each curve represents these values for a given percentage of carbon dioxide in the combustion gas. These curves are obtained in the manner previously described. In utilizing these curves for the determination of the average number of carbon atoms per molecule of hydrocarbon in a sample 55 of gas, a volume of gas corresponding to the volume employed for the production of the curves is subjected to combustion. The total heat of combustion per unit volume of this gas is determined and the amount of CO_2 in the combustion gas per unit volume of feed gas is measured. The amount of CO_2 found is utilized to select the 60 curve upon which the determined heat of combustion is read.

Let it be assumed that the curves were produced by burning the necessary number of 10 liter batches of gases of known composition. Let it be further assumed that 10 liters of sample gas evolved 30 gram-calories of heat per liter and produced 20 cc's of CO_2 per liter. The total heat of combustion, when read on curve "B," 75

would then give a point X which would indicate the average number of carbon atoms per molecule of hydrocarbon in the sample gas to be about 1.6. In other words, the sample gas would contain hydrocarbons higher than methane.

6 If there is no curve corresponding to the measured quantity of CO₂, a curve can be interpolated between and substantially parallel to the two curves representing the next higher and next lower CO₂ content.

10 In Fig. 3 is shown a series of curves obtained by plotting temperature rise at a given rate of flow against number of carbon atoms per molecule in the hydrocarbon contained in the gas undergoing test. Here again each curve represents the relationship between these values for a given volume of CO₂ in the exhaust gas. In this case, as previously pointed out, sample gas must be fed through the apparatus at the same 15 rate as that employed with the gases of known 20 composition used as the basis for the curves.

Also contemplated within the scope of the present invention is a method in which it is not necessary to measure the carbon dioxide produced from each sample of soil gas. Experiment has shown that over a given area, unless the area includes a swamp, the methane content of the soil gas remains substantially constant. In such areas it is possible, according to the present 30 invention, to detect changes in the content of the soil gas in paraffin hydrocarbons heavier than methane by simply passing samples of soil gas obtained at different points in the area through a combustion chamber at a selected rate 35 of flow and measuring the rise in temperature due to combustion. In this procedure, those points at which marked differences in temperature rise occur can be selected for a more accurate determination of the nature of the hydrocarbons in the samples collected at these 40 points. It is, of course, obvious, that, instead of passing the samples of gas from the different points through a combustion chamber at the same rate of speed, the same result can be obtained by subjecting the same volume of gas from the respective points to combustion and determining the heat of combustion of the several 45 samples.

The present invention is best employed in conjunction with known geological or geophysical methods for identifying sub-structures favorable to the accumulation of oil. For example, when a salt dome has been located by any one of the conventional geophysical methods, a sample of soil gas is taken at a depth of about 20 feet, directly over the peak of the dome, and other samples are taken at the same depth at points spaced from the first sampling point. The point at which a sample having the highest average 50 number of carbon atoms per molecule of hydrocarbon is found is then selected for the drilling operation.

When working according to the present invention, the average number of carbon atoms per hydrocarbon molecule in the soil gas becomes significant when it exceeds about 1.2. Generally an oil deposit will be indicated by an average 5 number of carbon atoms per hydrocarbon molecule in soil gas ranging from about 1.5 to about 2.2. An average number of carbon atoms per hydrocarbon molecule in soil gas less than 1.2 is generally indicative of a younger formation 10 such as a swamp or peat bed.

Having thus described the nature and objects of the present invention, what is claimed as new and useful and as desired to secure by Letters Patent is:

15 1. A method for locating sub-surface oil deposits which comprises collecting samples of soil gas at different points in an area under investigation, passing each sample through a combustion chamber maintained under conditions suitable for the combustion of the hydrocarbon content of the sample, measuring the temperature rise in the combustion chamber due to the combustion of the sample, comparing the combustion effects of the several samples to thereby determine the points at which samples having the greatest combustion effects were obtained, and subjecting gases from these points to examination 20 for hydrocarbons higher than methane.

25 2. A method for locating sub-surface oil deposits which comprises collecting samples of soil gas at a number of points in an area under investigation, passing each sample at the same selected rate of flow through a combustion chamber maintained under conditions suitable for the 30 combustion of the hydrocarbon content of the sample, comparing the increases in temperature in the combustion chamber due to the combustion of the several samples to thereby determine the points at which samples having the greatest 35 combustion effects were obtained and determining the carbon-hydrogen ratio of gases collected at these points.

40 3. A method for locating sub-surface oil deposits which comprises collecting samples of soil 45 gas at different points in an area under investigation, passing each sample, without pretreatment, at the same selected rate of flow through a combustion chamber maintained under conditions suitable for the combustion of the hydrocarbon content of the sample, measuring the temperature rise in the combustion chamber due to the combustion of the sample, comparing the increases in temperature in the combustion chamber due to the combustion of the several 50 samples to thereby determine the points at which samples having the greatest combustion effects were obtained and determining the carbon-hydrogen ratio of gases collected at these 55 points.

60 EDWARD B. PECK.
